(57) **CLAIM**

The ornamental design for a light, as shown and described.

DESCRIPTION

FIG. 1 is a perspective view of a light showing my new design;

FIG. 2 is a front view thereof;

FIG. 3 is a rear view thereof;

FIG. 4 is a side view thereof;

FIG. 5 is another side view thereof;

FIG. 6 is a top view thereof;

FIG. 7 is a bottom view thereof;

FIG. 8 is another perspective view thereof;

FIG. 9 is another perspective view thereof with the helmet attachment extended;

FIG. 10 is another perspective view thereof with the helmet attachment extended; and,

FIG. 11 is another perspective view thereof with the helmet attachment extended.

The broken lines throughout the drawing figures depict portions of the light that form no part of the claimed design.
